CLAIM

The ornamental design for a wreath, as shown and described.

DESCRIPTION

FIG. 1 is a top perspective view of a wreath showing my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is another perspective view thereof, shown in a folded configuration; and,

FIG. 10 is an enlarged portion view of encircled portion labeled, "10," in FIG. 1.

The dot-dashed broken lines shown in FIGS. 1 and 10 illustrate the boundary lines of the enlarged portion views of FIG. 10 and form no part of the claimed design. The even dashed broken lines shown in the drawings represent portions of the wreath that form no part of the claimed design.
